DESIGN FOR PACKING MATERIAL FOR FRAGILE ARTICLES

Ernest L. Shepard, Fairfield, Maine, assignor by mesne assignments, to The Coval National Bank of Portland, Portland, Maine, a national banking association, and William B. Nulty, Portland, Maine, as trustees

Application August 24, 1945, Serial No. 121,606

Term of patent 14 years

(Cl. D58—16)

To all whom it may concern:

Be it known that I, Ernest L. Shepard, a citizen of the United States, residing at Fairfield, in the county of Somerset, State of Maine, have invented a new, original, and ornamental Design for Packing Material for Fragile Articles, of which the following is a specification, reference being had to the accompanying drawings, forming part thereof.

Fig. 1 is a perspective view of packing material for fragile articles showing my new design and as seen when the packing material is closed,

and,

Fig. 2 is a similar view as seen when the packing material is open.

I claim:

The ornamental design for packing material for fragile articles, as shown.

ERNEST L. SHEPARD.

Certificate of Correction
